US0D1033167S

(12) United States Design Patent (10) Patent No.: US D1,033,167 S
(45) Date of Patent: * Jul. 2, 2024

(54) BOTTLE BAG WITH HANDLE

(71) Applicant: Shenzhen Jinchang Innovation Technology Co., Ltd., Shenzhen (CN)

(72) Inventor: Enqun Li, Shenzhen (CN)

(73) Assignee: Shenzhen Jinchang Innovation Technology Co., Ltd., Shenzhen (CN)

(*) Notice: Patent file contains an affidavit/declaration under 37 CFR 1.130(b).

() Term: 15 Years

(21) Appl. No.: 29/879,104

(22) Filed: Jun. 30, 2023

(51) LOC (14) Cl. 07-09

(52) U.S. Cl.

USPC D7/624.2; D3/202
